(57) **CLAIM**

The ornamental design for a ceiling fan blade arm, as shown and described.

DESCRIPTION

FIG. 1 is a perspective bottom front left view of a novel ornamental ceiling fan blade mounting arm.

FIG. 2 is a perspective bottom front right view of the blade mounting arm of FIG. 1.

FIG. 3 is a left side view of the blade mounting arm of FIG. 1.

FIG. 4 is a right side view of the blade mounting arm of FIG. 1.

FIG. 5 is a bottom view of the blade mounting arm of FIG. 1.

FIG. 6 is a top view of the blade mounting arm of FIG. 1.

FIG. 7 is a front side view of the blade mounting arm of FIG. 1; and,

FIG. 8 is a rear side view of the blade mounting arm of FIG. 1.

The broken line showing of the motor housing mounting end of the blade arm and upward protrusions is included for the purpose of illustrating environmental structure and forms no part of the claimed design.

1 Claim, 8 Drawing Sheets
